[57] CLAIM

The ornamental design for a desk tray, as shown and described.

DESCRIPTION

FIG. 1 is a top plan view of a desk tray showing my new design;

FIG. 2 is a bottom plan view thereof;

FIG. 3 is a left side elevational view, the right side elevational view being a mirror image thereof;

FIG. 4 is a front elevational view thereof;

FIG. 5 is a rear elevational view thereof; and

FIG. 6 is a top, left front perspective view thereof, drawn to a reduced scale.

FIG. 1.

FIG. 2.

FIG. 3.

FIG. 4.

FIG. 6.

FIG. 5.

FIG. 7.

UNITED STATES PATENT AND TRADEMARK OFFICE
CERTIFICATE OF CORRECTION

PATENT NO. : Des. 323,855

Page 1 of 6

DATED : Feb. 11, 1992

INVENTOR(S) : Mel Evenson,

It is certified that error appears in the above-identified patent and that said Letters Patent is hereby corrected as shown below:

The title page should be deleted to appear as per attached title page.

Drawing sheets 1-5 should be deleted to be replaced with drawing sheets 1-4 consisting of Figs 1-6, as shown on the attached pages.

Signed and Sealed this
Twenty-first Day of July, 1992

Attest:

DOUGLAS B. COMER

Attesting Officer

Acting Commissioner of Patents and Trademarks
